UNITED STATES PATENT OFFICE

LAWRENCE J. KUEHN, OF MILWAUKEE, WISCONSIN

OPHTHALMIC BRIDGE MOUNTING

Application filed May 20, 1929. Serial No. 364,434.

This invention relates to improvements in ophthalmic mountings.

It is the primary object of this invention to provide at greatly reduced expense a novel, simple, and practical form of ophthalmic mounting having improvements in the way of flexibility, lightness, ease of adjustment, facility of marketing, and freedom from breakage, which are inherent in its construction and are not available in any other form of mounting.

Matters of weight and flexibility are particularly apparent in an ophthalmic mounting. The present invention deals with the effect of flexibility not only from the standpoint of comfort to the wearer but also with reference to facility of manufacture, marketing and adjustment of the mounting. It is important, therefore, to note that the present invention seeks to provide advantages in the reduction of weight and increase of flexibility, not only without additional expense but at materially lower cost than the expense involved in the manufacture of types of mountings previously known.

It is a further purpose to produce for the first time a one-piece planiform blank for ophthalmic mountings, thus enabling such mountings to be stamped from sheet metal and solving problems heretofore presenting apparently insuperable obstacles to the production of such a blank. The bridge, arms and shanks are provided integrally, thus saving soldering operations heretofore necessary. Each mounting is fitted directly to the individual patient, thus eliminating all factory forming operations.

A further advantage of the present mounting, derived from its unusual flexibility and method of manufacture, is found in the fact that the mounting may be marketed in an unusual form, that is to say, in the form of a blank or flat article which may be molded to shape by the optician to suit the requirements of any patient as desired.

In the drawing:—

Fig. 1 is a view in perspective of a pair

of glasses assembled upon an ophthalmic mounting embodying this invention.

Fig. 2 is a perspective illustration of the blank from which the completed mounting is assembled.

Fig. 3 shows a mounting complete to the point of being merchantable but still in one plane with the exception of the added pads and straps for the lenses.

Fig. 4 shows the mounting partially modified and the intermediate form which it assumes between the form shown in Fig. 3 and the form shown in Fig. 1.

Like parts are identified by the same reference characters throughout the several views.

Ophthalmic mountings have heretofore usually been made of drawn metal such as gold or platinum wire, the component members having been bent to form at the factory and soldered together in a set or standardized way requiring modification by the optician in fitting glasses mounted thereon. Furthermore, the round or elliptical cross section of mounting heretofore employed has involved the use of an excess of material over that required for the flat sheet metal mounting which forms the subject matter of the present application.

The present invention contemplates a form of mounting which, except for the pads and straps, is integral in one piece, requiring no solder between the arms and shanks and bridge. It lends itself to economical production in quantity and can readily be modeled to any desired requirements of an individual patient from the flat or planiform shape in which it is sold.

Fig. 2 shows a blank in the form in which it is stamped from sheet metal for the manufacture of ophthalmic mountings in accordance with this invention. It is, as above indicated, planiform and includes integrally the bridge 5, arms 6, pad supports 7 and shanks 8. To render such a blank merchantable it is necessary, aside from polishing and the like, only to provide it with straps 9 and pads 10, the straps being preferably soldered to shanks 8 and the pads being 100

preferably riveted at 11 to the pad supports 7.

The fact that the extremely thin metal, of which the article shown in Fig. 3 is formed, has its width disposed in a vertical plane has the effect of making the mounting adequately rigid for the support of the lenses 12 with reference to each other while permitting the ready bending or formation of the parts in a horizontal direction. At the same time the component integral parts of the mounting are relatively flexible in a general horizontal plane so that they may easily be bent to the desired positions.

15 When an optician receives a product such as that illustrated in Fig. 3, the initial step in adapting it for the patient consists in arcuately curving the bridge portion 5 of the mounting to the form shown in Fig. 4. 20 This brings the pads 10 into suitable proximity to engage either side of the bridge of the patient's nose. In the course of this forming operation the height of the bridge of the mounting may be varied to suit the 25 requirements of the patient by bending the bridge portion 5 of the mounting in the plane of its minimum thickness if required. Ordinarily however, this will not be necessary.

30 With the bridge portion 5 of the article bent to the form illustrated in Fig. 4, the shanks 8 will be left projecting substantially horizontally and in parallel relation with their respective straps between them. In 35 order to complete the preparation of the mounting to receive the lenses 12, these straps are now bent back upon themselves as shown at 13 in Fig. 1. The point at 40 which the bend is made will determine the position of the lens with respect to the bridge, making it possible readily to adjust the individual lenses to positions most suited to the patient's requirements. The arc of 45 the bend will determine the spacing between lenses, thus facilitating also the adjustment of the mounting to the patient's requirements.

With the shanks 8 horizontal, the plane of the sectional portion of the bridge 5 will 50 not be vertical but will be somewhat inclined to conform to the incline of the patient's nose at this point. This relation is primarily determined by the angle of shanks 8 with respect to the bridge portion 5 of 55 the blank shown in Fig. 2. Obviously, however, the angularity between the members may be modified in the course of manually forming the mounting.

Any desired decoration in the way of embossing or the like may be added to the article without departing from the scope of

the invention. It is possible, for example, to emboss a design on the bridge portion 5 of the blank in the course of making the blank without additional expense.

It will be observed that the cost of 70 ophthalmic mounting embodying this invention is very materially less than the cost of manufacturing the standard wire mounting. In the first place one or more soldering operations are eliminated by the formation of 75 the blank in one piece. In the second place the manufacturer is not obliged to employ any shaping operations. In the third place the characteristics of the article lend itself to ready manipulation by hand in the course 80 of fitting the lenses to the patient, the required manipulation being seldom any greater and frequently less than that required for the adjustment of the standard mounting to the requirements of the particular patient.

The patient also shares in the benefit of 90 the invention since he has a mounting which is not only lighter and more flexible than the standard mounting in the directions required for ease of wearing, but he also has a mounting in which the metal is not fatigued by repeated working and in which the shape of the mounting is necessarily 95 made in accordance with his particular requirements.

I claim:

1. As a new article of manufacture, an ophthalmic mounting comprising a curved sheet metal bridge having its greatest width approximately vertical, shanks connected at acute angles to said bridge and projecting forwardly therefrom and bent back upon themselves, said bridge lying substantially wholly between the outer faces of the forwardly projecting portions of said shanks, and lens mounting means applied to the outer faces of the reversely bent portions of said shanks.

2. A one-piece planiform blank for ophthalmic mountings, said blank comprising a substantially rectilinear bridge portion, curved elbow portions at the ends of the bridge portion, substantially rectilinear lens mounting shank portions joined by said elbow portions to said bridge portion and converging from said elbow portions toward each other, arms diverging from each other and connected with said shank portions at positions offset from said elbow portions, and pad supports at the free ends of said arms, said portions being integrally connected and disposed in a common plane, whereby said blank may be formed to fit 125 individual requirements.
